UNITED STATES PATENT OFFICE

125,863

DESIGN FOR A COMBINATION DIRT CARRYING AND DUMPING VEHICLE

Gene L. Omon, Milwaukee, Wis., assignor to
Koehring Company, Milwaukee, Wis., a corporation

Application March 21, 1940, Serial No. 91,131

Term of patent 14 years

To all whom it may concern:

Be it known that I, Gene L. Omon, a citizen of the United States, residing at Milwaukee, in the county of Milwaukee and State of Wisconsin, have invented a new, original, and ornamental Design for a Combination Dirt Carrying and Dumping Vehicle, of which the following is a specification, reference being had to the accompanying drawing, forming a part thereof, in which:

Figure 1 is a rear perspective view of a combination dirt carrying and dumping vehicle from

the rear, the body being shown in tilted position to more clearly illustrate the control carriage.

Figure 2 is a front perspective view of the combination dirt carrying and dumping vehicle shown in Figure 1, the body being shown in un-tilted position.

I claim:

The ornamental design for a combination dirt carrying and dumping vehicle, substantially as shown.

GENE L. OMON.
